UNITED STATES PATENT OFFICE.

GEORGE FREDRIC OLSEN, OF LOS ANGELES, CALIFORNIA, ASSIGNOR TO GENERAL PETROLEUM CORPORATION OF CALIFORNIA, OF LOS ANGELES, CALIFORNIA, A CORPORATION OF DELAWARE.

TREATMENT OF LUBRICANT STOCKS.

No Drawing.

Application filed October 15, 1927. Serial No. 226,507.

My invention relates to the treatment of petroleum oil stocks consisting essentially of lubricants with liquefied sulfur dioxid.

The object of my invention is to so govern the course of the sulfur dioxid extraction as to obtain, from such viscous stocks, an extractive having such physical properties that it may be completely and readily removed from the remainder of the extracted oil.

10 The general and commonly used manner of treating petroleum distillates with sulfur dioxid is well known and understood. It consists, first, in liquefying gaseous sulfur dioxid by pressure and cooling; second, 15 in intermixing the heavy liquid thus produced with an oil to be treated, a portion of the oil passing into solution with the sulfur dioxid while another portion remains undissolved; third, in parting the bottom or solution layer from the upper or undissolved layer; fourth, in removing any entrained sulfur dioxid from the upper layer; fifth, 20 in distilling out of the lower layer the bulk of the sulfur dioxid—which is then condensed as before to enter a new cycle.

In the conduct of this process, no matter what the nature of the raw material, two fractions are obtained. The upper or undissolved layer consists of bodies rich in 30 hydrogen—saturated aliphatic hydrocarbons—purified to a high degree and well suited to their intended uses. Thus if the product is a gasoline it will have a relatively high gravity and be free from gum 35 forming constituents; if a kerosene it will have excellent burning qualities and will not gum the wick; if a lubricant it will have a high gravity, a flat viscosity curve and will be susceptible to treatment to an excellent color.

The lower or dissolved layer, after separation from the sulfur dioxid, consists of bodies rich in carbon—unsaturated aliphatic hydrocarbons and aromatic hydrocarbons. 45 These bodies have their uses, but in admixture with the saturated aliphatics they are simply impurities, and the object of the treatment is to remove them for the purification of the undissolved layer.

50 The separation of the upper layer from the lower layer must be complete in both directions if satisfactory results are to be obtained. That is to say, not only must the lower layer settle completely out of the

upper layer, but also the lower layer must 55 not entrain any appreciable quantity of the upper layer; otherwise an incomplete and wasteful separation will take place and the full benefit of the treatment will not be 60 realized.

In almost if not all cases the lower layer (after separation of the sulfur dioxid) will be found to be materially heavier and more viscous than the upper, and there is usually little difficulty in cleanly parting the lower 65 layer from the upper, but even with light oils there is often some difficulty in preventing entrainment of portions of the upper layer in the lower. In the case of lubricating oils, which at the low temperatures prevailing in this process are extremely viscous, it is often impossible to obtain a clean separation in either direction, so that the upper layer is seriously contaminated with the unstable unsaturated products which it is desired to remove, while the relatively valueless lower layer will entrain a serious proportion of the valuable upper layer. In extreme cases the two layers will emulsify, and 70 no separation whatever take place.

In order to avoid this difficulty and to make it possible to use this method to full advantage even on the heaviest lubricating oils, I make use of two steps not heretofore proposed, which steps may be used independently if desired, but are preferably used 75 in combination.

The first of these steps is to dilute the lubricant stock, prior to treatment, with 80 either a raw gasoline or kerosene, or one which has previously been subjected to the sulfur dioxid treatment. The object of this step is to facilitate the separation of the lower layer from the upper, both by reducing the viscosity of the upper layer (in 85 which the solvent will be found after the treatment) and by increasing the specific gravity difference by the lightening of the upper layer. Whether a raw or a previously treated solvent should be used is a matter of policy only. If a raw solvent be used it will be subjected to the treatment along with the lubricating oil, and when removed from the purified layer as herein-after described will be recovered as a purified material suitable for its proper use. On 90 the other hand, it may be more convenient as enabling the operator to better control 95 100 105

his dosage of sulfur dioxid, to cycle the purified solvent through a series of treatments. I do not limit my invention to either purified or unpurified solvent, nor to either gasoline or kerosene, either of which may be used to advantage, the only difference being that a larger proportion of the latter than of the former must be used, and when, in this specification or the appended claims, 10 I refer to a solvent I would be understood to mean a light petroleum product, of the general nature of gasoline or kerosene, either raw or previously purified.

Whichever solvent be used, a sufficient 15 quantity should be applied to obtain the desired results, which are, to materially lower the viscosity and to materially increase the A. P. I. gravity. This proportion will obviously depend on the gravity and the viscosity of the stock to be treated. I prefer to use such quantity of solvent as will bring the gravity up to at least 30° A. P. I. and the viscosity down to about 80 seconds at 100° F. Saybolt universal, but good results may 20 be had by using materially less proportions of solvent, and I do not limit my invention to any specific proportion thereof.

The second step in my invention, which as said may be used in connection with the 30 first step or independently thereof, consists in adding either to the oil to be treated or to the above said solution thereof, a material proportion of an extractive (recovered from the lower layer) from a previous treatment of gasoline or kerosene. As might be expected, it is a fact that the extractive from a gasoline is lighter and less viscous than the extractive from a kerosene, and so on down the scale until the extractive from a 40 very heavy lubricant is so viscous as to be practically solid. By the addition of a light and nonviscous extractive to a viscous oil to be treated, the extractive from the viscous oil is diluted by the non-viscous extractive 45 to such extent that entrainment of portions of the upper layer in the body of the lower layer may be entirely prevented and a perfectly clean separation may be obtained.

It is impossible to state any proportion 50 of light extractive to be used, as this proportion will vary widely, not only with the viscosity of the light extractive itself, but also and to a much greater extent with the natural viscosity of the extractive from the 55 oil to be treated. In some cases, as in the treatment of relatively low viscosity distillates, a small proportion of light extractive will be sufficient to render the lower layer sufficiently fluid to handle; in others, as for 60 instance heavy distillates or residua from asphaltic oils, a quite large proportion may be required. I therefore do not limit myself to any specific proportion of light extractive, and when I refer to a sufficient proportion of light extractive in this specifica-

tion or the attached claims, I would be understood as meaning—such quantity of an extractive obtained from a light petroleum product of the general nature of gasoline or kerosene as will dilute the extractive from the oil to be treated to a point where it will cease to entrain material proportions of the upper layer and at which a clean separation of the layers may be effected. In any specific case this proportion must be found by trial, 70 bearing in mind that the sole purpose of the addition of the light extractive is to lower the viscosity of the heavy or viscous extractive from the oil to be treated. 75

In the conduct of my invention no apparatus is required other than that in common use for the treatment of petroleum oils with liquefied sulfur dioxid and for the fractionation of petroleum products, nor is any special or unusual manipulation of the treatment 80 process itself called for, my invention residing in the steps above set forth, which are interposed in the usual treatment in their appropriate place. The following description applies to the use of both steps, but 85 will apply equally to the application of either step without the other.

Having selected a lubricant stock to be treated, I first dilute it with a solvent as 90 above described, using by preference a quantity sufficient to bring the A. P. I. gravity up to not less than 30° or the Saybolt viscosity at 100° F. down to not over 80 seconds. If the second step also is to be applied, I add to the above solution (or to the 95 oil itself in case the first step is to be omitted) a sufficient quantity of a light extractive. In any case the ingredients are thoroughly and carefully intermixed.

I then proceed to the extraction with 100 liquefied sulfur dioxid in the usual and well known manner, mixing for the usual time and allowing the mixture to form two layers by gravitation. If the proper proportions of solvent and of light extractive have been 105 used the separation will be rapid and complete. The lower layer is then withdrawn and the sulfur dioxid distilled out in the usual manner, after which the mixture of extractives is fractionally distilled in any 110 usual or preferred manner, the light fraction being recovered for reuse in a succeeding batch while the heavy fraction is put to such use as may be preferred, this heavy 115 fraction being identical with that which would have been obtained had the light extractive not been added, with the exception that it will be free from any portions of the material composing the upper layer. 120

The upper layer is then withdrawn from the extraction apparatus and freed from adhering traces of sulfur dioxid in the usual manner, and thereafter or concurrently separated from the solvent by fractional distillation 125 in any usual or preferred manner, the 130

solvent being recovered as a purified gasoline or kerosene, as the case may be, for use as such or for recycling, while the lubricating residue will be found to be entirely free 5 from bodies soluble in sulfur dioxid and thoroughly purified.

While the above described steps applied in the said treatment produce highly useful and valuable results, they are admittedly 10 open to the objection that an increased dose of sulfur dioxid is required to dissolve the light extractive added to the heavy oil. Under certain circumstances, as for instance where a relatively large proportion of gasoline and a relatively small proportion of lubricating oil are to be treated, the above process may be modified without in the least departing from the spirit of my invention, by simultaneously treating a gasoline or 15 kerosene and a lubricating oil, neither of which have previously been treated in this manner. If, for instance, three parts of a kerosene rich in extractives, such as California kerosene, be mixed with one part of a viscous lubricant and the mixture treated 20 with sulfur dioxid in the usual manner, the result will be a separation into two fractions, one containing a mixture of kerosene and lubricating oil, both thoroughly purified, and a mixture of light and heavy extractives. Proceeding in this manner both 25 the lubricating oil and the heavy extractive will be sufficiently diluted to obtain quick and clean separation of the layers. The mixture of kerosene (or gasoline, if preferred) and lubricating oil may then be submitted to fractional distillation, and the mixture of extractives may also be so separated if the use to which they are to be put 30 requires such separation. No more sulfur dioxid will be required than in the separate treatment of the two oils, in fact the consumption will usually be less on account of the reduced viscosity of the heavy extractive. 35 The only limitation to this method of applying my invention lies in the necessity of using materials having such boiling ranges 40 that they will not overlap and cause mutual contamination in the fractionation of the extracted oil.

I am well aware that the treatment of petroleum products with liquefied sulfur dioxid has heretofore been known and used, and

to such process I lay no claim, my invention being limited to such modifications of this 55 process as are set forth above and in the appended claims.

I claim as my invention:

1. In the fractionation and purification of viscous petroleum oils by treatment with 60 liquid sulfur dioxid, the steps comprising: diluting with a light petroleum product such portion of said viscous oil as is insoluble in said sulfur dioxid, and diluting with a light petroleum extractive, derived from a 65 light petroleum product, such portion of said viscous oil as is soluble in said sulfur dioxid.

2. In the fractionation and purification of viscous petroleum oils by treatment with 70 liquid sulfur dioxid, the steps comprising: diluting said viscous oil with a light petroleum solvent and adding to said diluted oil a sufficient quantity of a light petroleum 75 extractive obtained from a light petroleum product.

3. In the fractionation and purification of viscous petroleum oils by treatment with liquid sulfur dioxid, the steps comprising: adding to said viscous oil a sufficient quantity of a light extractive previously obtained from a light petroleum product and a solvent consisting of a light petroleum product. 80

4. As a step in the fractionation and purification of viscous petroleum oils by treatment with liquid sulfur dioxid: adding to said viscous oil, prior to said treatment, a sufficient quantity of a light extractive derived from a less viscous petroleum oil. 85

5. As a step in the simultaneous fractionation and purification of viscous petroleum oils and non-viscous petroleum oils by treatment with liquid sulfur dioxid: mixing with said viscous oil, prior to said treatment, such proportion of said non-viscous oil as will yield, under said treatment, a sufficient quantity of light extractive to materially reduce the viscosity of the heavy extractive simultaneously separated from said viscous oil by said treatment. 95

In witness that I claim the foregoing I have hereunto subscribed my name this 6th day of October, 1927.

GEORGE FREDRIC OLSEN.
